(57) CLAIM

The ornamental design for a hood, as shown and described.

DESCRIPTION

FIG. 1 is a front view of the hood showing my new design; FIG. 2 is a rear view thereof;

FIG. 3 is a left side view thereof;

FIG. 4 is a right side view thereof;

FIG. 5 is top view thereof;

FIG. 6 is a bottom view thereof; and,

FIG. 7 is a front right perspective view thereof.

The broken lines shown in the figures depict portions of the hood that form no part of the claimed design.
